CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA.

EJECTOR AND NOZZLE THEREFOR.

Application filed March 1, 1923. Serial No. 622,027.

To all whom it may concern:

Be it known that I, CHARLES E. LUCKE, a citizen of the United States, residing at New York city, county of New York, and 5 State of New York, have invented certain new and useful Improvements in Ejectors and Nozzles Therefor, fully described and represented in the following specification and the accompanying drawings, forming 10 a part of the same.

This invention relates to ejectors and nozzles therefor, and particularly to such ejectors of the class operated by a motive fluid such as water, or steam or other elastic fluid 15 for compressing and discharging air or other gas or vapor, as, for instance, in withdrawing air and non-condensed vapor from a steam condenser and compressing the withdrawn fluid to atmospheric or other 20 pressure for delivery.

One important object of the invention is to provide an improved ejector nozzle by which a single jet of any size may be used with the required entraining and compressing 25 efficiency, thus making unnecessary the present practice of using multiple jets for a large capacity, and further to provide such an ejector nozzle which may be adjusted to different capacities without substantial sacrifice of such efficiency. While the invention 30 is applicable to a water jet ejector, it will be described more particularly as applied to steam jet ejectors.

The steam jet now usually employed is of 35 circular section and the energy available for entraining and compressing is, for a given steam pressure and discharge pressure, substantially proportional to the cross-sectional area of the jet, that is to say, to the square 40 of the diameter of the jet at such cross-section. On the other hand, the entraining surface of the jet is proportional to the perimeter, or circumference, of the cross-section, that is to say, to the first power of the diameter 45 at such cross-section. The ratio of the perimeter to the area at the point of minimum cross-sectional area may be taken as one factor of the efficiency of the jet. Increase in the diameter of such circular jets lowers their efficiency because the ratio of 50 the perimeter to the area, viz, $\frac{4}{D}$, decreases with increase of diameter, D, so that the steam used per pound of air compressed increases. In other words, the steam at the

central portion of the jet can do little or no entraining of air. As a result, it has become the common practice to use multiple steam jets of relative small diameter for ejectors of large capacity, all of the jets discharging into one diffuser or combining tube. This increases the size and complication of the apparatus and involves difficulty in arranging the jets so as to secure free approach to all the jets of the air or other gas 60 to be entrained and compressed. Such circular jets, moreover, obviously cannot be adjusted for different capacities without varying the diameter of the jet tube in such a way as to change the character of the jet so that 65 the efficiency is reduced.

Furthermore, on account of the wide differences encountered in the conditions of operation, as, for example, between starting and regular full load operation, it is not 70 possible to employ a diffuser or combining tube which will operate with high efficiency under the varying conditions. Hence, the usual ejector has its diffuser or combining 75 tube of a compromise design, so that it will 80 continue to operate under varying conditions, but not with high efficiency.

By the present invention it becomes possible to avoid the above mentioned difficulties and to provide a construction of nozzle 85 for use either as a jet nozzle or as a diffuser or combining tube, or both, which will permit the ready adjustment of the cross-sectional area of such nozzle or nozzles to any 90 value between the limits for which such nozzle or nozzles is or are designed, while at the same time simultaneously adjusting the perimeter of the said cross-section in nearly or substantially the same proportion as the area is changed, so as to maintain as nearly 95 as possible a constant ratio of perimeter to area. In practice it is possible to design a nozzle whose throat or minimum cross-sectional area may be increased 100%, with less than a two per cent drop in ratio of perimeter to area, at said cross-section.

In accordance with the present invention, such a nozzle is made with two short sides and two very much longer sides, its longer sides being parallel in cross-section and either straight or curved, so that the nozzle will have a cross-section forming a more or less long and narrow strip of jet space. The width of this space strip is fixed at a value 105 as small as possible consistent with avoid- 110

- ing excessive wall friction losses. The length of the space strip is made great enough for the fluid capacity required. If the width of such space strip is very small 5 in proportion to the length, the ratio of area to perimeter approaches a constant value for any length of strip, so that such jets can be given the best ratio of width to length for efficient entraining and compressing 70 purposes, and this ratio can be substantially maintained regardless of the weight of steam passing through the jet, or the size of the jet, and thus the length may be adjusted relatively to a constant width of jet to suit 75 10 the capacity, without substantial loss of efficiency. When such a nozzle is used as an operating or jet nozzle, a corresponding construction of nozzle for the diffuser or combining tube is preferably used, the expansion 80 15 or contraction of the tube being in the same planes as that of the jet nozzle, and the length of the diffuser space in cross section may be adjustable relatively to a constant width, as in the case of the steam jet. 85 20 25 By the statement hereinabove made that the expansion or contraction of the combining tube is in the same planes as that of the jet nozzle, is meant that both nozzles are so arranged relative to each other that 90 30 an imaginary plane through the jet space of one nozzle parallel to those sides of such nozzle which are at the same distance apart throughout the length of the nozzle will also be parallel to the corresponding or similarly related sides of the other nozzle, 95 35 so that the expansion or contraction of the fluid in both nozzles will be in the direction of the homologous transverse axes of the two nozzles. 100 40 In the actual manufacture of steam jet 105 45 ejectors, it is necessary to meet a very wide variety of steam and air capacities, and of pressure and quality of steam supplied, pressure and amount of air entering the diffuser tube and fuel delivery pressure. This difficulty is multiplied when multistage 110 50 ejectors are used, as is now common practice. As a result, the steam nozzles and diffuser tubes, which must always be produced with great accuracy as to diameters and 115 55 angles of divergence or convergence, are expensive to make in the required varieties and degrees of accuracy and it is often necessary to use stock nozzles and tubes that are not exactly suited to the condition, to save 120 60 excessive costs, but with sacrifice of efficiency. In case an error is made it is not possible to correct it, and in case operating conditions are changed after installation, it cannot be met, and the ejector is either of 125 65 wrong capacity or very inefficient, or both, even though it may have been right at first. When the fluid jet is made, as in my 130 65 ejector, in the slot between two walls spaced apart as little as possible consistent with avoiding excessive percentages of jet energy loss due to wall friction, the ejector is efficient for any length of such slot, and any required capacity is obtained merely by determining the length of the slot which may 70 also be adjustable by hand. Any change of pressure requiring a change of angle of jet is easily met by shaping the narrow ends of the jet slot without changing the main side plates at all. Each of the main plates 75 that form the sides of the nozzle may be pieces cut from the same long piece. As a consequence, the manufacture is simplified, and it is possible to adjust for a new capacity in service, or to easily modify for new pressure conditions, and at all times to maintain 80 high efficiency. 85 90 In the accompanying drawings forming a part of this specification, there is shown for purpose of illustration, a steam jet air ejector embodying the invention in one of its preferred forms, and this construction will now be described and the features forming the invention then specifically pointed out in the claims. 95 100 105 110 115 120 125 130

nozzle space *a*, to vary the capacity without substantially changing the character of the steam jet and thus impairing its efficiency. As shown, both the end walls 13 are made 5 adjustable by hand operated screws 14 provided with locking nuts, so that the end walls 13 may be adjusted to the desired position and securely locked therein. The screws on the two walls are shown as adjustable independently of each other, but 10 obviously they may be arranged for adjustment of both simultaneously by a single operating means.

The jet nozzle above described may be 15 used with any suitable diffuser or combining tube, and the latter may be adjustable or not, but preferably and for the best results under all conditions the diffuser or combining tube is similarly made, as shown in 20 Fig. 4, with a relatively narrow and elongated combining space *b* formed by fixed side walls 15 and movable end walls 16, both of said end walls being made adjustable by hand operated screws 17, as in the case of 25 the steam jet. The adjustable end walls 13 and 16 are packed in any suitable manner against leakage, as indicated at 1.

It will be understood that the drawings 30 are largely diagrammatic and that the width of the steam and combining spaces respectively have been exaggerated relatively to their lengths, in Figs. 1 to 5, for purpose of illustration, and that the construction shown and described is only for purpose of illustration of one embodiment of the invention, and 35 may be varied widely within the invention as defined by the claims.

Fig. 6 gives diagrammatically an idea of what the proportions of the jet slot may be 40 in cross-section to obtain the full benefits of the invention. If it be assumed that when the end walls are at the position of minimum jet orifice, the length of the slot will be 25 times the width of the slot, and when the 45 end walls are adjusted away from each other where the length of the jet slot is 50 times the width of the slot, there can be obtained a variation in slot area of one hundred per cent—that is to say, the maximum jet area at the smallest section will be 50 double the minimum jet area at the same section, while, on the other hand, the ratio of perimeter of slot to area of slot has changed less than 2 per cent. Of course, at 55 other cross-sections of the jet, the variation in said ratio will be greater depending upon the slope of the inner walls of the nozzle, but by keeping the width as small as possible consistent with a small loss of jet energy 60 due to wall friction, and obtaining the desired cross-sectional area of jet by using a slot which is long relative to its width, the variation in the ratio of perimeter to area 65 may be kept relatively low, and hence the variation in efficiency may be maintained

within satisfactory limits. In Fig. 6 the slot is indicated as about 0.1 inch in width, and at its minimum area it has a length of 2.5 inches, while at its maximum area it has a length of 5 inches. This principle applies 70 both to the jet nozzle and to the diffuser or combining tube.

What is claimed is:

1. An ejector having an operating fluid nozzle and combining tube, each formed 75 with at least two opposite sides parallel to each other in cross-section, the expansion or contraction of the operating fluid nozzle and combining tube being in the same planes.

2. An ejector having an operating fluid 80 nozzle and a diffuser or combining tube, each formed with at least two opposite sides parallel to each other in cross-section, the expansion or contraction of the operating fluid nozzle and combining tube being in the 85 same planes, and means for adjusting the length of the space between the two parallel opposite sides of the operating fluid nozzle to vary its capacity.

3. An ejector having an operating fluid 90 nozzle and a diffuser or combining tube, each formed with at least two opposite sides parallel to each other in cross-section, the expansion or contraction of the operating fluid nozzle and combining tube being in the 95 same planes, and means for adjusting the length of the space between the parallel opposite sides of the nozzle and tube to vary their capacity.

4. An ejector having a nozzle formed with 100 a fluid space elongated in cross section and its opposite walls defining the width of the fluid space parallel to each other in cross-section, and means for adjusting at least one end wall of the nozzle to vary the length of 105 the fluid space in cross-section.

5. An ejector having a nozzle serving as an operating or jet nozzle, and formed with 110 a fluid space elongated in cross-section and its opposite walls defining the width of the fluid space parallel to each other in cross-section, and means for adjusting at least one end wall of the nozzle to vary the length of the fluid space in cross-section.

6. An ejector having a nozzle serving as a 115 diffuser or combining tube, said nozzle being formed with a fluid space elongated in cross section and its opposite walls defining the width of the fluid space parallel to each other in cross-section, and means for adjusting at least one end wall of the nozzle to vary the length of the fluid space in cross-section.

7. An ejector having an operating fluid 125 nozzle and a diffuser or combining tube, each formed with a fluid space elongated in cross-section and having its opposite walls defining the width of the fluid space parallel to each other in cross-section, and means for adjusting the end walls of the nozzle and 130

- tube to vary the length of the fluid space in cross-section.
8. In a steam air ejector, the combination with a steam nozzle having a jet space with one dimension in cross-section narrow relatively to the other, of an air-receiving chamber, and a diffuser or combining tube receiving the steam and air and having its combining space of two different dimensions in cross-section with the larger and smaller dimensions in the same planes as the larger and smaller dimensions of the steam nozzle.
9. In a steam air ejector, the combination with a steam nozzle having a jet space with one dimension in cross-section narrow relatively to the other, of an air-receiving chamber, and a diffuser or combining tube receiving the steam and air and having its combining space of two dimensions in cross-section, and means for adjusting the nozzle to vary the larger dimension of the jet space.
10. In a steam air ejector, the combination with a steam nozzle having a jet space with one dimension in cross-section narrow relatively to the other, of an air-receiving chamber, and a diffuser or combining tube receiving the steam and air and having its combining space of two dimensions in cross-section, and means for adjusting the nozzle to vary the larger dimension of the jet space.
11. In a steam air ejector, the combination with a steam nozzle having a jet space with one dimension in cross-section narrow relatively to the other, of an air-receiving chamber, and a diffuser or combining tube receiving the steam and air and having its combining space of two different dimensions in cross-section with the larger and smaller dimensions in the same planes as the larger and smaller dimensions of the steam nozzle.

ing the steam and air and having its combining space of two different dimensions in cross-section, and means for adjusting the nozzle and diffuser to vary the larger dimension of the jet and combining spaces.

12. An ejector nozzle having two fixed side walls separated from each other to form a slot whose width of opening at any cross-section is small relatively to its length, said ejector also having at least one movable end wall to move into the slot to vary the length of said slot, said parts being so proportioned that at the smallest section of the nozzle the length of the slot at its minimum length is at least 25 times the width of the slot.

13. An ejector nozzle having two fixed side walls separated from each other to form a slot whose width of opening at any cross-section is small relatively to its length, said parts being so proportioned that at the smallest section of the nozzle the length of the slot is at least 25 times the width of the slot.

In testimony whereof, I have hereunto set my hand.

CHARLES E. LUCKE.
